BUSHING EXTRACTOR AND INSERTER

Leon B. Miller, Brooklyn, N. Y.

Application September 8, 1933, Serial No. 688,570

1 Claim. (Cl. 29—88.2)

This invention relates generally to devices for simultaneously removing and replacing bushings, and particularly to a combination bushing remover and inserter specially adapted for re-bushing of bearings in kingpin brackets for automobiles.

One of the prime objects of this invention is to provide a device designed to simultaneously remove at least two worn-out or defective bushings, and by the same operation to insert new bushings in the places of the old.

Another object of this invention is to provide a device of this kind which will be inexpensive as to its manufacture, simple as to its construction and entirely self-contained and so constructed that it always remains in alignment over its entire length during the operation of replacing bushings.

A still further object of this invention is to provide in such a device means whereby the operation of the tool is facilitated through the employment of either a press, a vise or other suitable devices, whereby the two ends of the tool may be thrust against one another.

Another object of this invention is to provide in combination with the tool, means for operating the tool without the employment of outside agencies.

A still further object of this invention is to provide in connection with such tool, exchangeable bushing abutting means or collars adapted to be replaceable for any desired size of bushings.

The foregoing and still further objects of this invention will be more fully apparent from the following description, in connection with the accompanying drawing, forming part of my disclosure, but by no means intended to limit me to the actual construction shown, and in which

Fig. 1 illustrates a preferred form of my tool, partially in section, as it is applied to the kingpin bearings of an automobile.

Fig. 2 illustrates a modified form of my invention adapted to be operable by means of a thread and nut.

Fig. 3 is still another modification of my tool provided with exchangeable bushing abutments or collars.

Fig. 4 illustrates a modified arrangement of my tool members operatively mounted with an independent pilot, shaft or bolt, and

Fig. 5 represents a still other modification of my tool.

My invention preferably embodies a male and a female member, both members being guided relative to one another and each having one or

more bushing receiving shanks equipped with bushing end abutments, all arranged during operation in symmetric order. The tool is so designed that the members may be forced towards one another, after the desired bushings are placed against their corresponding abutments. The operation of the tool is uniform, that is the members are forced uniformly at the same speed against one another. Through this concerted movement, the new bushings are first brought in contact with their respective old bushings of the kingpin bearings, and as the movement progresses, the new bushings gradually force out the old bushings into the space between the bearings provided in the kingpin structure, and finally take the place of the expelled bushings.

Referring now specifically to the figures, numeral 10 denotes the wheel shaft of kingpin structure 11 consisting of brackets 12 and 13 in which are provided bearings 14 and 15. Old bushings 16 and 17, shown in broken lines in Fig. 1, are in a partially driven-out position having been forced out by new bushings 18 and 19, shown in full lines. These latter bushings are engaged by abutments 20 and 21 respectively, which abutments are formed as the members are reduced to inner shank extensions 22 and 23. Female member 24 and male member 25 of the tool are both provided with end heads 26 and 27, respectively. Adjacent to heads 26 and 27 are the largest shanks or recessed portions 28 and 29 which are separated from the heads by abutment faces 30 and 31. Forming a continuation of shanks 28 and 29, are reduced portions or shanks 32 and 33 which have a lesser diameter than the former shanks. Steps 34 and 35 connect sections 28 and 32 and 29 and 33, and form abutment faces for bushings.

As will be seen from the drawing, these gradually recessed shank portions are arranged symmetrically to one another at both female and male members. The latter has a centrally located guide shaft or pilot 36 extending from the smallest reduced portion 23, whereas the female member has a central bore 37 in which shaft 36 is guided. Each corresponding pair of the reduced portions of the tool members are intended for the reception of corresponding sizes of bushings. In Fig. 1 there are illustrated three recessed portions for three sizes of bushings. Be it understood, however, that any smaller or greater number of shank portions may be arranged to serve specific purposes. The tool shown in Fig. 1 is adapted to be operated by a press or vise, in that the heads of the tool members are

engaged by the jaws of such press or vise, and as the latter are operated, the members are drawn towards one another.

The modified form of my invention illustrated 5 in Fig. 2 comprises a male member 38 and a female member 39, both similar in construction to members 25 and 24 of Fig. 1. Each of the tool members are provided with symmetrically grouped, shank or recessed portions, diminishing 10 in sizes from their respective heads 40 and 41 towards their inner ends. The largest recessed portions are indicated at 42 and 43, the next smaller shanks are numbered 44 and 45 and the innermost portions 46 and 47. Faces 42' and 43', 15 44' and 45', 46' and 47' serve as abutments for the outer ends of new bushings intended to replace and force out worn, old bushings from aligned bearings.

The centrally located guide shaft 48 of the 20 male member, registers with the central bore 49 of the female member, and is shown to be threaded at 50, which threaded portion is engaged by operating nut 51, bearing against head 41. This modified form of my device is 25 intended to be operated without the agency of a press or similar device and is entirely self-contained. After the desired pair of new bushings is placed over the corresponding recessed portions of both members, guide shaft 48 of the male member 38 is slipped through both the old bushings of kingpin bearings, and female member 39 is then brought over the shaft. Now nut 51 is operated until the inner ends of the new bushings engage the outer ends of the old bushings in 35 the bracket. Having made certain that the bushings are in proper alignment, the operation of the nut continues until the old bushings are completely forced out and replaced by the new ones.

40 The arrangement of a series of recessed portions diminishing in sizes in the direction from the tool member heads inwards is intended for the purpose of permitting the use of the tool for variously sized bushings in different makes of cars, where the variations in inner diameters of the bushings are sufficiently great to provide adequate abutting surfaces, as illustrated in Figures 1 and 2. In the event, however, where the diameters of the bushings differ only slightly, 45 sufficiently wide abutting surfaces have to be provided in a different way, as for instance shown in Fig. 3.

This modified form comprises a short male member 52 and a correspondingly short female member 53, both consisting of heads 54 and 55 and recessed portions 56 and 57, respectively, the latter forming integral parts of the heads and serving for the reception of the largest bushing the tool is adapted for. A guide shaft 58 is fixedly secured in reduced portion 56 and is adapted to 50 register with the central bore of female member 53. Operatively engaged by shaft 58 are concentrically drilled, removable abutments or collars 59 and 60, consisting of reduced portions 61 and 62, and annular abutting beads 63 and 64 respectively. These beads are of sufficient width to 55 fully engage the end faces of corresponding bushings, when the latter are placed over their reduced portions.

Below collars 59 and 60 are illustrated similar, 60 but heavier exchangeable collars 65 and 66, intended for bushings of larger diameters and are designed to take the place of the smaller collars, when larger bushings are to be replaced by the tool. Obviously, any number and sizes of re-

placeable collars may be provided with each tool, thereby enhancing the latter's applicability for any required work. In Figure 3, a smooth guide shaft is illustrated, which may be readily replaced by one provided with a thread, similar 80 to that described in Fig. 2.

It will be noted that in each of the forms shown the tool members are so arranged as to guide one another and to remain in alignment during operation, which is essential for proper replacement of bushings in aligned bearings. In Figures 1 and 2 the guide shafts are shown to form integral parts of the male members. It is obvious, however, that they may be constructed in a way similar to that shown in Fig. 3 where the shaft 90 is threaded into the male member.

Inasmuch as the pilot or shafts and the guide bores are the essential means for guiding and aligning the two members, it is readily conceivable to employ two hollow members, similar to 95 the female members shown, and to guide and align them by means of a pilot. Such arrangement is indicated in Fig. 4, in which numeral 69 denotes the independent guide pilot registering with the bores of left and right members 100 68 and 67. Each of the members may be constructed either in the manner of female members 24 and 39 (Figures 1 and 2), or may take the form of female member 53 (Fig. 3), with which latter construction exchangeable collars are to be employed. Such arrangement may be operated either in a press, or by using a threaded pilot 105 similar to that of Fig. 2.

Referring now to Fig. 5, this construction is 110 intended for the removal and insertion of bushings of one size only. In this illustration it will be observed that the bearings and bushings of the kingpin bracket, known in automotive parlance as "spindle", are not of equal length. Thus bearing 70 is somewhat longer than bearing 71, 115 and old bushings 72 and 73 and new bushings 74 and 75 correspond in length to that of their respective bearings.

The tool itself consists of two entirely identical 120 hollow members 76 and 77 and a shaft 78 in the form of a bolt passing through the bores of both members, which serve as guides and bearings for the shaft. At one end of the shaft a head 79 is provided, while its other end is threaded at 80 and is engaged by nut 81. 125 Shanks 82 and 83 are twice as long as their corresponding bushings so that the old, expelled bushings are piloted during their removal, whereby their proper engagement by the new bushings is assured. The heads of the 130 members are provided with bushing engaging seats or faces 84 and 85 and with chamfered surfaces 86 and 87, the latter adapted to facilitate the deflection of shavings from the newly forced-in bushings. A marking groove 88 at the 135 center of shank 83 constitutes the only easily ascertainable difference between the two members 76 and 77, since the variation in length between their shanks is very small. This groove is intended to indicate whether or not the correct bushing is slipped over the right shank. When the bushing covers or partially covers the marking groove, after it is brought in contact with seat 85, it is an indication that the wrong 140 tool member was employed. The operation of the tool is very similar to that explained in connection with Fig. 2.

While I have illustrated only four modifications of my tool in specific forms, it is quite evident that other designs containing the under- 145

lying principles of my invention may be developed for various purposes, and that changes and improvements may be made in the course of the manufacture of my tool. I, therefore, reserve 5 for myself the right to make such changes or improvements as may become necessary, all within the broad scope of my idea, as set forth in the appended claim.

I claim:

10 In a device for extracting two old, and simultaneously inserting two new bushings in place of the old ones, a pair of substantially symmetrical bushing engaging members adapted to be simultaneously movable towards one another, 15 common guide means for said members centrally located relative to the latter, and adapted

to keep the members in alignment during operation, said members provided with abutments for engaging one end of the new bushings, the free ends of the latter adapted to serve as abutments for the old bushings, the new bushings being intended to serve as extracting means for the old bushings, said members provided with elongated shanks extending from their abutments, these shanks being of sufficient length and diameters for fully accommodating, internally engaging and guiding both new and old bushings during the entire operation, the shank of one of said members provided with an annular marking groove for determining the correct bushing size intended for each member.
